[57] CLAIM

The ornamental design for a furniture leg boot, as shown and described.

DESCRIPTION

FIG. 1 is a top, front and left side perspective view of a furniture leg boot showing my new design;

FIG. 2 is a top plan view thereof; and,

FIG. 3 is a bottom plan view thereof; and, FIG. 4 is a side elevational view thereof, said view being the same for all side elevational views.

The broken line showing of a partial furniture leg is for illustrative purposes only and forms no part of the claimed design.
